UNITED STATES PATENT OFFICE.

THOMAS J. LITTLE, JR., OF PHILADELPHIA, PENNSYLVANIA, ASSIGNOR TO WELSBACH LIGHT COMPANY, OF GLOUCESTER CITY, NEW JERSEY, A CORPORATION OF NEW JERSEY.

HIGH-POWER LAMP.

No. 895,032.

Specification of Letters Patent.

Patented Aug. 4, 1908.

Application filed November 18, 1903. Serial No. 181,603.

To all whom it may concern:

Be it known that I, THOMAS J. LITTLE, Jr., a citizen of the United States, residing at the city of Philadelphia, in the county of Philadelphia and State of Pennsylvania, have invented certain new and useful improvements in High-Power Lamps, of which the following is a specification.

Objects of the present invention are, first, to simplify and improve the construction and operation of high power lamps; second, to facilitate the starting of such lamps in such a way that even unskilled labor can be employed for this purpose; third, to provide reliable and efficient working parts for the lamp; and fourth, to provide a high power lamp suitable for commercial purposes and work. Other objects of the invention will appear from the following description and the invention itself will be finally claimed.

Figure 1, is an elevational view of a lamp embodying features of the invention. Fig. 2, is a view partly in section of one side of the upper portion of the lamp. Fig. 3, is a similar view of the other side of the lamp. Fig. 4, is a detail view, principally in section, illustrating the upper portion of the lamp. Figs. 5 and 6, are sectional views taken on the line 5—6, of Fig. 4, and illustrating two positions of the valve. Figs. 7 and 8, are respectively a side elevation and a top or plan view of the pawl shown in Fig. 3, and Fig. 9, is a sectional view of the door shown in Fig. 3.

In the drawings 1, is a spider provided with depending rods or bolts 2, which carry the plate 3, which constitutes the top of the lantern proper and which is shown as provided with a curved rim that projects laterally. The displacer cylinder 4, is arranged so that its lower end projects through the plate 3, and its upper end is provided with an outward flange which together with a gasket as of asbestos is clamped between the spider 1, and the upper head 5, which is bolted to the spider, thus the cylinder is well supported and is sufficiently free to permit of its expansion and contraction under temperature changes. The upper head carries the power cylinder displacer a.

6, is a baffle consisting of thin plates united at their rims and supported at their hubs. It is mounted upon the cylinder and serves to insure the requisite difference in temperature at the ends thereof.

7, are radiator plates. Their hubs as well

as the hub of the baffle 6, consist of a number of points or projections 8, and this construction induces rapid dissipation of heat.

9, is a plate with an upwardly extending rim arranged beneath the spider 1. It constitutes a base for the housing or casing 10, which may be provided with openings that admit air to cool the working parts.

11, is a casting bolted to the upper head 5, and provided with a centrally arranged neck 12, which is connected with the valve casing 13. Within the casting 11, is arranged a fan chamber which may be covered as by a plate 14, held to place by screws 15, Fig. 3. This fan chamber has a downward opening which communicates with the burner pipe 16, so that a discharge is provided from it into the burner pipe. The plate 14, is provided with an intake having a door 17, which can be more or less opened so as to regulate the quantity of air admitted. This door is pivoted to a stud between the head of which and the door is interposed a spiral spring 18. This spring serves to hold the door in any position to which it has been adjusted and the construction as a whole is durable and well adapted to its purpose. The casting 11, is also provided with a gas conduit 19, which does not communicate with the fan chamber but does communicate with the burner pipe 16. The arbor 20, which carries the fan is journaled in the casting as is also the shaft 21.

22, are oil cups formed integral with or attached to the casting and they serve to lubricate the parts to which they are adjacent. Interposed between the displacer piston rod and a crank pin is a connecting rod 23, one end of which is pivoted to a coupling 24, affording lateral motion in respect to the rod. The other end of this rod 23, is provided with a fork pivoted to a sleeve 25, slidable on the crank pin. This construction compensates for irregularities in alinement and insures satisfactory operation.

26, is a wheel connected with the shaft 21, and it is provided with a crank pin 27, on which is mounted a slidable sleeve to which is connected the forked end of a connecting rod 28, and this connecting rod is connected with the piston of the working cylinder. The wheel 26, is peripherally grooved as is also a wheel connected with the shaft 20. A belt 29, consisting of a spirally wound wire passes around these wheels and runs in their

grooves and it serves to transmit motion to the fan. This spirally coiled wire belt is capable of withstanding the heat and exposure to which it is subjected and at the same time is very efficient and durable.

30, is an oil cup which serves to lubricate the cylinder and piston rod. From the upper part of the valve casing 13, extends a pilot tube 31, having its lower end arranged to light the burners to be presently described. As shown this pilot tube is arranged to support a continuous flame of which the size may be regulated by the screw 32.

15 33, is a heating burner supply pipe and it extends from the lower part of the valve casing downward and carries at its end a Bunsen burner 34, having an air inlet as at 35. This Bunsen burner 34, is provided and arranged for initially heating the lower end of the cylinder 4, before the lighting burner 36, does so and in this way the engine is started. The valve casing is provided with a plug valve seat which is arranged at an inclination and there is also an opening through it which accommodates the nut 37, that holds the plug valve 38. Gas is led to this valve by the port 39, Fig. 5, and from this valve gas is led to the burner pipe 19, by way of the port 40, and to the heating burner by way of the port 41. When the plug 38, is in the position shown in Fig. 5, no gas reaches either the lighting or heating burners. As the plug is turned in a clockwise direction, gas at first reaches the heating burner 34, by way of the port 41, and the circumferential notch 42. By and by the notch gets out of line with the port 41, and the diametral opening 43, comes in line with the port 40, thus feeding gas to 40 the lighting burner and extinguishing the heating burner.

The plug 38, is mounted upon the end of an operating rod 44, in such a way that the plug turns with the rod but has some motion in respect to it so as to compensate for any lack of perfect alinement. The lower end of the rod 44, passes through the plate 9, and baffle 6, and is guided thereby. 45, is a thumb nut for turning the rod and of course the plug 38. 50 The motion of the rod is limited by the pin 46, which works between suitable stops 47 and 48, Fig. 3. The operating rod 44, carries an adjustable coupling 49, to which is pivoted a pawl 50. The pawl is fitted with a back 55 stop 51, arranged to collide with the rod and with two skew teeth 52. The spring 53, may be employed for holding the pawl up to its work. The teeth 52, engage the teeth of a wheel 54, carried by the shaft 21, in a manner 60 to be presently described. Assuming that the pilot light 31, is burning and that the operating rod is in the position shown in Fig. 3, with the stop 46, in contact with the stop 47, the valve plug is in substantially the position 65 shown in Fig. 5, and no gas passes through it.

The operating rod is then turned until the pawl 50, contacts with the teeth of the wheel 54, whereupon it is permitted to remain at rest for a short time. Under these conditions gas passes by 41, to the heating burner pipe 33, so that the heating burner 34, is lighted from the pilot light and its flame serves to warm the lower end of the cylinder 4, thus bringing the engine into condition for running as soon as it is started. The operating rod 44, is then turned further in the same direction with the result that the skew teeth 52, in passing impart a motion of rotation to the wheel 54, which starts the engine. Further motion of the rod is checked by a contact of the stops 46 and 48. This last motion of the rod shifts the plug 38, into such position that the supply of gas to the heating burner 34, is cut off while a supply of gas is delivered by the port 43, to the lighting burner and it then not only furnishes light by heating a mantle or mantles but also drives the engine. To extinguish the light, the rod 44, is returned to its initial position. Upon the plate 3, may be arranged a sheet of asbestos or the like 55, and the rim of this plate is provided on one side with openings and on the other side with an upwardly inclined pin 56. The ring 57, is provided with hooks 58, which detachably take into the openings and it is also provided with a loosely riveted link adapted to engage and disengage the pin 56, so that the ring can be turned about the hooks as a hinge and the link can be made to engage and disengage the pin or the whole ring can be readily detached. The fact that the link is loosely riveted affords it sufficient movement and at the same time enables it to withstand the heat to which it is exposed.

59, is a netting as of wire which incloses and supports a glass globe. The netting is attached to the ring by means of S-shaped hooks 60, either of the lobes of these can be passed over the pins to accommodate the netting to irregularities in the sizes of globes.

61, is a netting which may be placed as shown in Fig. 1, and it serves to admit cool air to the upper portion of the displacer 4.

The structure as a whole is suspended as for example from a gas pipe by means of a coupling formed as at 62, on the valve casing.

It will be obvious to those skilled in the art to which my invention appertains that modifications may be made in details without departing from the spirit thereof, hence I do not limit myself to the precise construction and arrangement of parts hereinabove set forth and illustrated in the accompanying drawings, but

Having thus described the nature and objects of my invention, what I claim as new and desire to secure by Letters Patent is:

1. In a lamp the combination with an

- illuminating burner and a hot air engine operated thereby, of a spider provided with an opening for the reception of the flanged end of the displacing cylinder of the engine, 5 a plate provided with two openings through one of which passes the burner and through the other of which passes the closed end of said cylinder and which properly positions the burner in respect to the closed end of the 10 cylinder and affords the cylinder freedom for expansion and contraction, rods for suspending the plate from the spider, and a cylinder head secured to the spider and engaging the flanged end of the cylinder, substantially as 15 described.
2. In a lamp the combination with an illuminating burner and a hot air engine and a fan and the connections for driving the fan, of a spider from which the displacer cylinder 20 of the engine depends and on which is superposed the working cylinder of the engine and the fan and their connections, and a plate depending from the spider and provided with openings through which are arranged in 25 proper relative positions the end of the displacer cylinder and the illuminating burner, substantially as described.
3. In a lamp the combination with an illuminating burner and a hot air engine and a fan, of a casting constituting a frame for the engine and fan parts, a cylinder head which carries said casting, a displacer cylinder depending from the head, a spider to which the head is connected, and a plate depending 35 from the spider and having openings for the displacer cylinder and the burner, substantially as described.
4. In a lamp the combination with an illuminating burner and an engine driven 40 thereby and a fan, of grooved pulleys and a spirally wound belt operatively arranged in respect to the grooved pulleys whereby power is transmitted from the engine to the fan, substantially as described.
- 45 5. In a lamp the combination with an illuminating burner and an engine driven thereby and a fan driven by the engine and having proper connections, of means for transmitting motion which comprises crank pins, sleeves, endwise movable on the crank pins, and forked arms engaging the sleeves whereby motion may be transmitted notwithstanding the heat to which the parts are subjected, substantially as described.
- 55 6. In a lamp comprising in its construction a hot air engine and an illuminating burner and fan mechanism, the combination of a frame consisting of a spider constituting a support for the engine and fan parts and 60 from which the displacer cylinder depends, and of a plate provided with openings for the burner and displacer cylinder and of rods depending from the spider and carrying the plate, substantially as described.
7. In a lamp the combination of an engine, 65 a lighting burner, an engine shaft, a gas controlling valve, an operating rod for the latter, and pawl-and-ratchet connections between the valve and engine shaft whereby the latter is started at the proper time in respect 70 to gas admission, substantially as described.
8. In a lamp the combination of an engine, a pilot light, a starting burner, a lighting burner, a valve and its operating handle for supplying gas to the starting burner to start 75 the engine and for supplying gas to the lighting burner, and connections between the engine and the valve whereby the former is started prior to the lighting of the lighting burner, substantially as described.
9. In a lamp the combination of an engine having a ratchet wheel, a starting burner, a lighting burner, a valve for controlling the supply to said burners, a stop for said valve, an operating rod for the valve, and a pawl 85 carried by said rod and arranged to cooperate with the ratchet wheel, substantially as described.
10. In a lamp the combination of a ratchet wheel, a plug valve, an operating rod, a 90 frame through which the operating rod passes and which carries the valve and wheel, a pawl carried by the operating rod, and a swivel connection between the rod and valve, substantially as described.
11. In a lamp the combination of a fixed ring having diametrically arranged openings and an upwardly inclined pin, a ring having hooks for engagement with the openings and a loosely riveted link adapted to engage and 100 disengage the pin, and a globe carried by the ring, substantially as described.
12. The combination in a lamp of a spider, a lamp structure including a burner supported thereby rods depending from the 105 spider, a displacer cylinder of a hot air engine depending from the spider, and cooling devices mounted on the cylinder and provided at their hubs with points or projections which induce rapid dissipation of heat and 110 having at their edges engagement with said rods, substantially as described.
13. In a lamp the combination of an engine shaft having a ratchet wheel, a frame having a valve seat inclined in respect to said shaft, 115 a plug valve having an operating rod arranged at an inclination to the shaft, and a pawl mounted on the rod and having skew teeth which compensate for the inclination of the axes of the shaft and rod, substantially 120 as described.
14. The combination of a valve casing, a lamp having all of its parts suspended from said casing, said casing provided with an opening and having to one side of the opening a support and to the other side of said opening a gas way having formed through it an inclined open ended valve seat, a plug 125

valve adapted to said seat and attaching means arranged in the opening and engaging the plug valve, substantially as described.

15. The combination in a lamp of a frame 5 having a plug valve seat and a rod bearing, an engine shaft carried by the frame, a plug valve held to said seat, a rod connected with the valve and guided by the bearing, and a pawl-and-ratchet connection interposed be- 10 tween the shaft and rod, substantially as described.

16. In a lamp the combination of an engine, a lighting burner, a gas distributing valve having a rod, and means for causing movement of the valve rod to mechanically start 15 the engine, substantially as described.

In testimony whereof I have hereunto signed my name.
